US00D790275S

(12) **United States Design Patent** (10) **Patent No.:** **US D790,275 S**
(45) **Date of Patent:** **** Jun. 27, 2017**

(54) **BLADE**

- (71) Applicant: **SharkNinja Operating LLC**, Newton, MA (US)
(72) Inventor: **David M. Audette**, Webster, MA (US)
(73) Assignee: **SHARKNINJA OPERATING LLC**, Newton, MA (US)

(**) Term: **15 Years**

(21) Appl. No.: **29/563,238**

(22) Filed: **May 3, 2016**

Related U.S. Application Data

(62) Division of application No. 29/502,792, filed on Sep. 19, 2014, now Pat. No. Des. 758,799.

(57) **CLAIM**

The ornamental design for a blade, as shown and described.

DESCRIPTION

FIG. 1 is a top, front, right side perspective view of a blade showing my new design;

FIG. 2 is a bottom, front, right side perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a right side elevational view thereof; and,

FIG. 8 is a left side elevational view thereof.

The dashed broken lines represent unclaimed portions of the blade and form no part of the claimed design. The dash-dot-dash broken lines define boundaries of the claimed design and form no part of the claimed design.

1 Claim, 3 Drawing Sheets
